Primary Examiner — Eric L Goodman*Assistant Examiner* — Darcey E Heflin(74) *Attorney, Agent, or Firm* — Perkins Coie LLP(57) **CLAIM**

The ornamental design for a bottle ring, as shown and described.

DESCRIPTION

FIG. 1 is an exploded view of the a bottle ring;
 FIG. 2 is an isometric view of the bottle ring of FIG. 1 when positioned on a bottle;

FIG. 3 is a frontal view of the bottle ring of FIG. 1 when positioned on a bottle;

FIG. 4 is a zoomed-in version of the isometric view of the bottle ring of FIG. 1;

FIG. 5 is a top view of the bottle ring of FIG. 4;

FIG. 6 is a frontal view of the bottle ring of FIG. 4; and,
 FIG. 7 is a cross-sectional view of the bottle ring of FIG. 4

along the plane identified in FIG. 5.
 The broken-line disclosure represents portions of the bottle ring or bottle which form no part of the claimed design.
